UNITED STATES PATENT OFFICE.

FERDINAND MAIER, OF NEW YORK, N. Y.

PHONOGRAPH FRICTION TOY.

1,355,612.

Specification of Letters Patent.

Patented Oct. 12, 1920.

Application filed April 11, 1918. Serial No. 228,046.

To all whom it may concern:

Be it known that I, FERDINAND MAIER, a citizen of the United States, and resident of New York city, in the county of New York and State of New York, have invented certain new and useful Improvements in Phonograph Friction Toys, of which the following is a specification.

My invention relates in general to an attachment for phonographs of the flat disk type and specifically relates to an organization of a phonograph and an attachment to constitute a toy designed to be actuated simultaneously with the playing of an appropriate record on the phonograph.

One of the primary objects of the invention is to utilize the movement of a phonograph turn-table for the purpose of actuating a toy. The physical embodiment of the invention as herein illustrated contemplates the actuation of the toy through a frictional driving connection with the turn-table, but this disclosure is only suggestive of two ways for utilizing the power system of the phonograph, and a different physical embodiment of the invention is disclosed in my co-pending application, entitled Phonograph centrifugal toy, filed under even date.

Various other objects and advantages of the invention will be in part obvious from an inspection of the accompanying drawings and in part will be more fully set forth in the following particular description of one form of mechanism embodying my invention, and the invention also consists in certain new and novel features of construction and combination of parts hereinafter set forth and claimed.

Referring to the accompanying drawings:—

Figure 1 is a view in side elevation of the top of a phonograph showing the turn-table in a vertical sectional view taken axially through the same and showing one embodiment of my invention; and

Fig. 2 is a view similar to Fig. 1 showing a second form of the invention.

In both figures, there is shown a phonograph 10, including the motor driven shaft 11, upon which is positioned a flat disk form of turn-table 12. The turn-table is provided with a felt top 13, for carrying the playing disk record 14 in operative relation with the reproducer 15, all as is usual in well known forms of such devices.

There is shown in connection with both figures a toy mounted in fixed position adjacent the turn-table and including a rotary element in frictional driving connection with the turn-table. In the form of the invention illustrated in Fig. 1, the toy is merely shown diagrammatically, it being understood that the driven belt 16 may lead to any of the toys or machines now known and which are usually driven by an electric or some other motor. The transmission element shown in Fig. 1, and which may symbolically represent the toy includes a stand 17 fastened to the frame 18 of the phonograph to which stand is pivoted a horizontally extending journal sleeve 19, free to move about the horizontal axis provided by the pivot pin 20. The sleeve 19 constitutes a bearing for a shaft 21, to one end of which shaft is affixed a friction wheel 22, held in light bearing frictional engagement with the playing disk record 14 adjacent its periphery by means of a coil spring 23. The spring has one end fixed to the sleeve and the other end fixed to the relatively stationary stand 17. A pulley 24 is fixed to the outer end of the shaft 21 and constitutes the driving member for the belt 16.

In the form of the invention illustrated in Fig. 2, the toy is in the form of a horse-drawn wagon 25, provided with wheels 26, held by means of the weight thereon in frictional driving engagement either with the turn-table, with the outer edge of the disk as shown in Fig. 1, or in engagement with a track 27 revolved by the turn-table.

The wagon may be of any form and in the device illustrated may be considered as a fire apparatus, preferably of that type of such devices, in which the rotation of the wheels will cause some parts of the driver and the horses to move and thus to simulate the act of driving. The toy is held from rotation with the turn-table by means of a flexible arm 28. One end of the arm is attached to the wagon, and opposite end is attached to the heavy base 29 held to the frame 18 by its weight, or by fastening means as shown in Fig. 1.

The track 27 may obviously extend beyond the periphery of the turn-table and in Fig. 2 is shown positioned to coincide with the turn-table leaving space at its center for the positioning of a small playing disk 14. In order to give a scenic effect to

the track the inner edge thereof may be outlined by an upstanding circular wall 30, upon which may be painted scenes designed to combine with the representation of the 5 track portion 27 to represent a race track, street or other desired scene.

In operation, and with the desired toy in operative engagement with the turn-table or parts actuated thereby, a suitable playing disk is positioned to be revolved by the 10 turn-table and the reproducer positioned as is usual in setting a phonograph in its playing operation. The turn-table is rotated, the playing disk sounds and the toy is actuated. In the modification shown in Fig. 2 15 and supposing that the wagon 25 represents a fire engine, the playing disk could be arranged to sound fire bells, cheers, and other noises incident to an apparatus of the fire department responding to an alarm.

In this way not only may the power mechanism of the phonograph be utilized for the actuation of mechanical toys but by using an appropriate playing disk the interest in the toy may be enhanced.

Having thus described my invention, I claim:—

1. In a device of the class described, the 30 combination of a phonograph turn-table, a player disk mounted on said turn-table, a race track mounted on the turn-table to revolve therewith and encircling the player disk, and a toy held in frictional engagement with said race track, said track and 35 toy having relative movement when the turn-table is revolved during the playing of the disk.

2. An attachment for the turn-table of a 40 phonograph comprising a track provided with a player-disk-opening and adapted to constitute one element of a friction drive, and a toy provided with a revoluble member constituting an element coacting with the first named element to complete the 45 friction drive and mechanism actuated by said friction drive.

3. An attachment for the turn-table of a

phonograph comprising a track adapted to constitute one element of a friction drive, and a toy provided with a revoluble member constituting an element coacting with the first named element to complete the friction drive and mechanism actuated by said friction drive, said attachment provided with an upstanding wall.

4. In a device of the class described, the combination with a phonograph turn-table provided with a space to accommodate a playing record, of an attachment for said turn-table for engaging the same exteriorly 60 of said record-accommodating-space, and revolving therewith, and a toy relatively fixed in place and provided with a revolving wheel in frictional engagement with said revolving attachment and driven thereby.

5. An attachment for the turn-table of a phonograph comprising a track having a relatively large opening in the center thereof to accommodate a player record, the under side of said track provided with a turn-table engaging surface adapted to engage the turn-table frictionally so as to be rotated thereby, a toy provided with means for holding the same substantially in fixed position, said toy including a wheel adapted 75 to be disposed in bearing engagement with the top of the track whereby the wheel is revolved by the rotating track.

6. An attachment for the turn-table of a phonograph comprising a track having a 80 relatively large opening in the center thereof to accommodate a player record, the under side of said track provided with a turn-table engaging surface adapted to engage the turn-table frictionally so as to be rotated thereby and the upper side of said 85 track provided with a toy-engaging surface adapted to engage a rotating element of a toy to actuate the same.

Signed at New York City in the county 90 of New York and State of New York this 15th day of March, A. D. 1918.

FERDINAND MAIER.
